US00D837311S

(12) **United States Design Patent** (10) **Patent No.:** **US D837,311 S**
(45) **Date of Patent:** **** Jan. 1, 2019**

(54) **FIGURINE**

(71) Applicant: **Mattel-MEGA Holdings (US), LLC**,
El Segundo (CA)

(72) Inventors: **Benoit Vézina**, Montreal (CA); **Eric Perreault**, St Basile le Grand (CA)

(73) Assignee: **Mattel-MEGA Holdings (US), LLC**,
El Segundo, CA (US)

(**) Term: **15 Years**

(21) Appl. No.: **29/611,325**

(22) Filed: **Jul. 20, 2017**

(51) **LOC (11) Cl.** **21-01**

(52) **U.S. Cl.** USPC **D21/658**

(57) **CLAIM**

The ornamental design for a figurine, as shown and described.

DESCRIPTION

FIG. 1 is a top isometric perspective view of a first embodiment of a figurine showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a bottom plan view thereof;

FIG. 8 is a top isometric perspective view of a second embodiment of a figurine showing the new design;

FIG. 9 is a front elevational view thereof;

FIG. 10 is a rear elevational view thereof;

FIG. 11 is a side elevational view thereof;

FIG. 12 is an opposite side elevational view thereof;

FIG. 13 is a top plan view thereof; and,

FIG. 14 is a bottom plan view thereof.

The broken lines and unshaded areas are included to illustrate parts of the article's appearance that form no part of the claimed design.

1 Claim, 14 Drawing Sheets
